Primary Examiner — Paula Greene(74) Attorney, Agent, or Firm — RG Patent Consulting, LLC; Rachel Gilboy(57) CLAIM

I claim the ornamental design for a cremation urn, as shown and described.

DESCRIPTION

FIG. 1 is a front elevational view of the cremation urn embodying the design of the present invention.

FIG. 2 is a side elevational view thereof.

FIG. 3 is a side elevational view thereof.

FIG. 4 is a rear elevational view thereof.

FIG. 5 is a top plan view thereof; and,

FIG. 6 is a bottom plan view thereof.
